DESIGN FOR AN ASH TRAY

Conrad Dahl, Chicago, Ill., assignor to Anna T.
Green, Philadelphia, Pa.

Application March 2, 1933. Serial No. 47,391

Term of patent 3½ years

To all whom it may concern:

Be it known that I, CONRAD DAHL, a citizen of the United States, residing at Chicago, in the county of Cook and State of Illinois, have invented a new, original, and ornamental Design for an Ash Tray, of which the following is a specification, reference being had to the accompanying drawing, forming a part hereof, in which:

Fig. 2 is a side elevational view.

Fig. 3 is a plan view.

Fig. 4 is a perspective view.

I claim:

The ornamental design for an ash tray substantially as shown.

CONRAD DAHL.
